UNITED STATES PATENT OFFICE.

GEORGE W. HEY, OF SYRACUSE, NEW YORK.

ELECTRICAL APPARATUS.

SPECIFICATION forming part of Letters Patent No. 514,462, dated February 13, 1894.

Application filed May 9, 1892. Serial No. 432,284. (No model.)

To all whom it may concern:

Be it known that I, GEORGE W. HEY, of Syracuse, in the county of Onondaga, in the State of New York, have invented new and useful Improvements in Electrical Apparatus, of which the following, taken in connection with the accompanying drawings, is a full, clear, and exact description.

My invention relates to improvements in an apparatus for electrically transmitting signals, particularly designed for use in telephonic and telegraphic service, and is somewhat similar to the apparatus described and claimed in my pending application, Serial No. 430,274, filed April 22, 1892, and it consists, essentially, in a central or main telephone station, a series of branch circuit wires connected to the main station, branch stations connected to branch circuit wires, automatically operating switches between the main station and the branch circuit wires, and between the several branch stations and their respective circuit wires whereby the branch stations of separate circuits may be connected through the medium of the main station, or the branch stations of one of the circuits may be connected without the main station and in the detail construction and arrangement of the parts, all as hereinafter more particularly described and pointed out in the claims.

In describing this invention, reference is had to the accompanying drawings, forming a part of this specification, in which like letters and figures indicate corresponding parts in all the views.

Figure 1 is a diagrammatic view, illustrating the general construction and arrangement of one form of apparatus for carrying out my invention. Fig. 2 is a diagrammatic view of one of the series of branch stations of the apparatus shown at Fig. 1. Fig. 3 is a vertical sectional view of one of the detached switches, adapted to be interposed between the separate or independent circuit wires and the main and branch stations, shown as inclosed in a casing or box. Fig. 4 is a front face view of the detached switch shown at Fig. 3, illustrated as in its normal position. Fig. 5 is a front face view, similar to Fig. 3, representing the terminals of the switch as just on the point of engaging one another for permitting the passage of the current to the station con-

nected thereto for ringing its signal. Figs. 6, 7, 8, 9, 10, 11 and 12 are vertical sectional detail views, representing the terminals of one of the switches in various positions for clearly illustrating the action of said switch; and Figs. 13 and 14 are detail sectional views, taken on lines 13—13, —14—14—, Fig. 4.

In my aforesaid previous application I have called attention to the well known fact that in practice it is customary to connect several telephones to a single main or circuit wire and call the required one from a central or main station on the wire, by means of a peculiar call consisting of a particular number or duration of vibrations of the signal bell, and that in this case the signal for each telephone is transmitted throughout the whole number and is rung simultaneously by all of the signal bells, thus occasioning considerable inconvenience and annoyance, owing to the continued ringing of the bells and the liability of mistaking a telephone call. I am aware, however, that certain telephone call bell systems have been devised for calling a predetermined station of a series on a single line, but as usually constructed, these systems are dependent in operation either upon complicated mechanism, wiring, electric motors, currents of different quality and non-automatic resetters, or are so constructed and arranged as to momentarily close the signal-operating circuits in stations other than the one to which the predetermined call is addressed.

My present signaling system, like the one set forth in my aforesaid application, Serial No. 430,274, is entirely differentiated from devices of this character, in that, it is extremely simple and practical in construction and operation; does not, for its practical operation, require complicated wiring, electric motors, or currents of different quality. Moreover, it is so constructed and arranged, that the switches at each station are automatically reset as soon as one of the signal-operating circuits is closed by the switch at any station of the series on the same circuit wire and that the signal-operating circuit of the station to which the call is addressed is positively and effectually closed without requiring momentary closing of the signal-operating circuits at the other stations of the series.

I have illustrated, described and claimed in my aforesaid application an apparatus for electrically transmitting signals whereby a number of telephones may be connected upon a main wire and any particular telephone called at will from the main station without operating the signal bells of the other telephones.

In this invention I have sought to still further simplify the art of transmitting signals for telephonic, telegraphic and similar purposes so as to enable one station to positively and practically call another without the necessity of calling upon the central station for connection to the other station, or the inconvenience and annoyance of ringing the signal bell upon any station other than the required one.

It is well known that at present each separate station is compelled to apply to the main station for connection to another and that the main station is filled with a net-work of wires and an extensive and complicated switch board requiring constant care and numerous attendants; consequently, as by my improved invention I enable one station to call another on either side thereof without the aid of the main station, great inconvenience and annoyance is obviated and a great saving in the time, labor, cost and maintenance of telephonic systems effected. To effect this result, I connect to the main station a series of branch circuit wires, provide each of these circuit wires with a series of branch stations, and interpose between each of the circuit wires and the main and branch stations automatically operating switches so arranged, connected and constructed that any one is automatically closed and the others automatically returned to their normal position when the currents passed through the branch circuit wires are of a predetermined number and duration, whereby one may be automatically closed while the others remain open.

In order that my invention may be readily understood, I have here shown as one of the forms embodying the same, a simple telephonic system, but it will be evident, as will be hereinafter reiterated, that my invention is not limited to this particular form of mechanism, or to use upon telephonic systems.

—A—represents the main station, —B—C—D—E—F—G—, —O—P—P’—P²—P³—P⁴—, —R—S—S’—S²—S³—S⁴— branch stations, and —H—T—U— branch circuit wires connected to the main and branch stations.

I have here illustrated the corresponding divisions or sections —H²¹—H²²—H²³—H²⁴—H²⁵—H²⁶—H²⁷—, —T²¹—T²²—T²³—T²⁴—T²⁵—T²⁶—T²⁷—, and —U²¹—U²²—U²³—U²⁴—U²⁵—U²⁶— and —U²⁷— of the branch circuit wires —H—T—U— as substantially parallel, and at Fig. 1 have shown a series of six stations connected to each circuit wire, the parts of the first branch station of each series being diagrammatically illustrated and the remaining stations being indicated by rectangles,

as the space is insufficient to diagrammatically indicate the parts of each station. The inner sections —H²¹—, —T²¹—, —U²¹— of the wires —H—T— and —U— are provided with terminals —1—2— and —3— connected to one end of the levers —H’—T’— and —U’— of a switch —H²—. The other end of the levers —H’—T’— and —U’— are each alternately movable between terminals —4—5—, —6—7—, and —8—9—. The terminals —4—6— and —8— are connected respectively to the inner ends of movable switches or keys —H³—T³— and —U³— having their opposite ends interposed between the terminals —10—11—, —12—13—, and —14—15—. The terminals —10—12— and —14— are connected respectively to one end of the wires —H⁴—T⁴— and —U⁴— having their opposite ends connected to the upper end of the wire —H¹¹—, the lower end of which is connected to the ground —H¹²—; and the terminals —11—13— and —15— are each connected to the upper end of a wire —H⁵— having its opposite end secured to the positive pole of a suitable battery or other electrical generator —H⁶—.

The negative pole of the battery —H⁶— is connected by a wire —H¹³— to the ground wire —H¹¹—. The wires —H⁴—T⁴— and —U⁴— are provided with the respective loops —H²⁸—, —T²⁸—, and —U²⁸— connected to magnets —H²⁹—T²⁹—U²⁹— adapted to close automatic switches —h—, —t—, and —u— interposed in the electric circuit —H³¹— to which are connected suitable signals as electric bells —H⁷—T⁷— and —U⁷—.

The circuit —H³¹— consists of a suitable battery or electric generator —H³²—, a positive wire —H³³— having branches —H³⁴—H³⁵—H³⁶— leading to the respective switches —h—, —t—, —u— and the return wire —H³⁷— having branches —H³⁸—, —H³⁹—, —H⁴⁰— leading from said switches —h—, —t—, —u—. These switches —h—, —t—, —u— are normally open or out of circuit and as will be presently described, are of such construction as to be closed one at a time.

The bell —H⁷— is of the usual construction and consists of a magnet —H⁸— connected to the branch —H³⁸—, a clapper or hammer —H⁹— and a vibrating shell —H¹⁰— of the same construction as the shell —B¹⁰— shown in cross section at Fig. 3. The bells —T⁷— and —U⁷— are composed of corresponding parts —T⁸—U⁸—, —T⁹—U⁹—, and —T¹⁰—U¹⁰—, the magnets —T⁸— and —U⁸— being connected, respectively, to the branches —H³⁹— and —H⁴⁰— of the wire —H³⁷—. When the switch —h— is closed, or in circuit the current is passed through the wire —H³³—, branch —H³⁴—, branch —H³⁸—, magnet —H⁸— and return wire —H³⁷—, thus bringing the bell —H⁷— into action by striking the clapper —H⁹— upon the vibrating shell —H¹⁰—. On the contrary, when the switch —t— is closed, the current passes from the wire —H³³— through the branches —H³⁵— —H³⁸— to the magnet —T⁸— and thereby causes the signal or bell

—T⁷— to operate and when the switch —u— is open, the current passes from the wire —H⁸³— through the branches —H³⁶—H⁴⁰— to the magnet —U⁸— and brings the bell —U⁷— 5 into action.

The rear end of the first section —H²¹— of the branch circuit wire —H— is connected to a terminal —b— of the first telephone station of the series connected to said wire, as best 10 seen at Fig. 2.

The outer end of a switch lever —B'— of the switch —B²— swings upon the terminal —b— and the other end of said lever is movable between terminals —b'—b²—. The terminal —b'— is connected to one end of a switch or key —B³— having its opposite end movable between terminals —b³—b⁴— connected, respectively, to one end of the section —H²— of the circuit wire —H— and to the upper end 25 of a wire —B⁵— connected to the positive pole of a battery —B⁶—.

The negative pole of the battery —B⁶— is connected by a wire —B⁴— to the ground —H¹²—. The section —H²²— of the wire —H— extends from the terminal —b³— through, (or in suitable proximity to) a suitable magnet —b⁵— for operating the switch —i— of an independent circuit —I— connected thereto and extends to the terminal —c— of the second telephone station —C— of the series connected to the wire —H— corresponding to the terminal —b— of the former station. This latter or second telephone station —C—, as best seen at Fig. 2, is provided with a switch lever —C'—, switch —C²—, switch or key —C³—, wires —C⁴—C⁵—, battery —C⁶—, terminals —c—c'—c²—, —c³—, —c⁴—, magnet —c⁵—, switch —j—, and independent circuit —J— corresponding to the 35 similar parts —B'—B²—, —B³—B⁴—, —B⁵—, —B⁶—, —b—b'—, —b²—, —b³—, —b⁴—b⁵—, —i— and —I— of the telephone station —B—, and the stations —D—, —E—, —F—, and —G— are each provided with corresponding 40 parts —D'—, —D²—, —D³—, —D⁴—, —D⁵—, —D⁶—, —b—, —b'—, —b²—, —b³—, —b⁴—, —b⁵—, —k—, —K—, —E'—, —E²—, —E³—, —E⁴—, —E⁵—, —E⁶—, —e—, —e'—, —e²—, —e³—, —e⁴—, —e⁵—, —l—L—; —F'—, —F²—, —F³—, —F⁴—, —F⁵—, —F⁶—, —f—, —f'—, —f²—, —f³—, —f⁴—, —f⁵—, —m—, —M—, and —G'—, —G²—, —G³—, —G⁴—, —G⁵—, —G⁶—, —g—, —g'—, —g²—, —g³—, —g⁴—, —g⁵—, —n—, —N—; the sections —H²³— 55 —H²⁴—H²⁵—H²⁶— of the wire —H— being connected, respectively, to the terminals —c³—d—, —d³—e—, —e³—f—, —f³—g—, and to the magnets —c⁵—d⁵—e⁵—f⁵—. The extreme end section —H²⁷— of the wire —H— 60 extends from the terminal —g³— of the sixth telephone station through the magnet —g⁵— and to the ground —H¹²—. It will thus be seen that the branch wire —H— forms part of a circuit consisting, essentially, of the ground wire —H¹¹—, negative wire —H¹³—, battery —H⁶—, positive wire —H⁵—, switch or key —H⁸—, terminal —4—, switch lever —H'—, 65

terminal —1—, sections —H²¹—H²²—H²³—H²⁴—H²⁵—H²⁶—H²⁷— of the wire —H—, the terminals —b—c—d—e—f—g—, switch levers —B'—C'—D'—E'—F'—G'—, terminals —b'—c'—d'—e'—f'—g'—, switches or keys —B³—C³—D³—E³—F³—G³—, and the magnets —b⁵—c⁵—d⁵—e⁵—f⁵— and —g⁵—.

When desired to call from the main station 75 any of the branch stations connected to the main wire —H—, the key or switch —H⁸— is depressed into contact with the terminal —11— and the current passes from the battery —H⁶— through the wire —H⁵—, terminal —11—, switch or key —H³—, terminal —4—, switch lever —H'—, terminal —1— and wire section —H²¹— to the first telephone station, thence through the terminal —b—, switch lever —B'—, terminal —b'—, switch or key 80 —B³—, terminal —b³—, wire section —H²²—, and magnet —b⁵— of the station —B—, thence through the wire sections —H²³—H²⁴—H²⁵—H²⁶— to the stations —C—D—E—F—G— and through their corresponding parts —c—C'— 85 c³—C³—c⁵—; —d—D'—d'—D³—d³—d⁵—; —e—E'—e'—E³—e³—e⁵—; —f—F'—f'—F³—f³—f⁵—; and —g—G'—g'—G³—g³—g⁵—, and finally through the wire section —H²⁷— to the ground —H¹²—. 95

If desired the section —H²⁷— instead of running to the ground may return to the negative pole of the battery —H⁶— of the main station —A—.

The battery —H⁶— may consist of any desired form of electric generator, the switches —H²—H³—B²—B³—C²—C³—D²—D³—E²—E³—F²—F³— and —G²—G³— may be suitably varied or constructed and the magnets —b⁵—c⁵—d⁵—e⁵—f⁵— and —g⁵—, may be of any suitable construction capable of being energized or brought into action by the passing current and the particular form of wiring connecting the aforesaid parts may be varied at will.

The main station —A— is provided with 110 a transmitter —a⁷— connected by a wire —a⁸— having a primary coil —a⁹— to the negative pole of the battery —H⁶— by a portion of the ground wire —H¹¹— and the wire —H¹³— and is connected by a wire —a¹⁰— to 115 a terminal —a¹¹— with which is registered one end of a switch lever —a¹²— hinged to a terminal —a¹³— connected by a wire —a¹⁴— with a positive pole of the battery —H⁶—. This main station is also provided with a receiver —a¹⁵— connected to the ground wire —H¹¹— by a wire —a¹⁶— provided with a secondary coil —a¹⁷— surrounding the primary coil —a⁹— and connected by a wire —a¹⁸— to the terminals —9—7— and —5— with which 120 the switch levers —U'—T'— and —H'— are separately registered in order to connect the receiver —a¹⁵— with the circuit wires —U—T— and —H—. 125

The lever —a¹²— is independently connected to the levers —H'—T'— and —U'— by the respective insulating bars —a¹⁹—a²⁰— and —a²¹— having open slots at their ends engaged with pins —a²²— projecting from said 130

lever. Consequently, when either of the switch levers H' — T' — U' is rocked from its position, shown at Fig. 1, into engagement with the corresponding one of the terminals 5 — 7 or 9 , the lever a^{12} is simultaneously shifted into engagement with the terminal a^{11} , and, as said, one of the levers H' — T' — U' is withdrawn to its normal position, a suitable spring a^{23} retracts the lever a^{12} .

W represents a switch at the main station A for connecting the adjacent ends of the circuit wires H — T — U together and although this switch may be of any desired form, size, and construction, it is here illustrated as composed of levers w — w' and w^2 . The lever w is mounted on an insulating post w^3 and its opposite extremities are adapted to register with terminals w^4 — w^5 upon the wires H — U for connecting said wires together. The levers w' — w^2 are mounted on the respective insulating posts w^6 — w^7 and their opposite ends are adapted to register with the terminals w^8 — w^9 and w^{10} mounted on the respective wires H — T — U for connecting the wire T to either of the wires H or U .

The telephone station B connected to the circuit wire H is provided with a transmitter b^7 , wire b^8 , primary coil b^9 , wire b^{10} , terminal b^{11} , lever b^{12} , terminal b^{13} , wire b^{14} , receiver b^{15} , wire b^{16} , secondary coil b^{17} , wire b^{18} , and insulating bar b^{19} corresponding to the like parts a^7 — a^8 — a^9 — a^{10} — a^{11} — a^{12} — a^{13} — a^{14} — a^{15} — a^{16} — a^{17} — a^{18} and a^{19} of the main station A .

The remaining stations C — D — E — F and G connected to the wire H are provided with transmitters c^7 — d^7 — e^7 — f^7 — g^7 ; wires c^8 — d^8 — e^8 — f^8 — g^8 ; primary coils c^9 — d^9 — e^9 — f^9 — g^9 ; wires c^{10} — d^{10} — e^{10} — f^{10} — g^{10} ; terminals c^{11} — d^{11} — e^{11} — f^{11} — g^{11} , switch levers c^{12} — d^{12} — e^{12} — f^{12} — g^{12} , terminals c^{13} — d^{13} — e^{13} — f^{13} — g^{13} , wires c^{14} — d^{14} — e^{14} — f^{14} — g^{14} ; receivers c^{15} — d^{15} — e^{15} — f^{15} — g^{15} ; wires c^{16} — d^{16} — e^{16} — f^{16} — g^{16} ; secondary coils c^{17} — d^{17} — e^{17} — f^{17} — g^{17} ; wires c^{18} — d^{18} — e^{18} — f^{18} — g^{18} , and insulating bars c^{19} — d^{19} — e^{19} — f^{19} — g^{19} of similar construction and arrangement to the corresponding parts b^7 — b^8 — b^9 — b^{10} — b^{11} — b^{12} — b^{13} — b^{14} — b^{15} — b^{16} — b^{17} — b^{18} and b^{19} of the main station A .

b^{20} represents a switch or key having one end registered with the terminal b^{21} on the wire B^5 and the other adapted to be brought into contact with the terminal b^{22} on the wire section H^{22} for passing a current from the wire B^5 through the stations C — D — E — F and G in the same manner as a current is passed from the wire H^5 through the stations B — C — D — E — F and G .

The wires C^5 — D^5 — E^5 and F^5 are provided with terminals c^{21} — d^{21} — e^{21} and

f^{21} , the stations C — D — E — F with keys c^{20} — d^{20} — e^{20} — f^{20} , and the wire sections H^{23} — H^{24} — H^{25} — H^{26} — H^{27} with terminals d^{22} — e^{22} — f^{22} — g^{22} corresponding to the like parts b^{20} — b^{21} — b^{22} of the wire B^5 , station B , and wire section H^{22} .

When desired to call the main station from the first station of the series connected to the wire H , the switch or key B^3 is depressed into contact with the terminal b^4 and the electric current passes from the battery B^6 through the switch or key B^3 , terminal b' , wire B^5 , terminal b^1 , switch lever B' , terminal b , the main wire section H^{21} , the terminal 1 , switch lever H' , terminal 4 , switch or key H^3 , terminal 10 , wire H^4 , the magnet H^{29} of the bell H^7 , and ground wire H^{11} . The bell H^7 is thus operated and attracts the attention of the operator at the central office and immediately he moves the switch levers H' — a^{12} into contact with the terminals 5 and a^{11} and the user of the telephone at the branch station B moves the switch levers B' — b^{12} into contact with the terminals b^2 — b^{11} , whereupon the current from the battery H^6 passes through the wire a^{14} , terminal a^{13} , switch lever a^{12} , terminal a^{11} , wire a^{10} , transmitter a^7 , wire a^8 , primary coil a^9 and wires H^{11} — H^{12} to the negative pole of the battery H^6 . An induced current is then generated in the secondary coil a^{17} which is connected to the ground by the wire H^{11} and the portion of the wire a^{16} interposed between the coil a^{17} and the wire H^{11} and said current is passed from the coil a^{17} through the opposite portion of the wire a^{16} , the receiver a^{15} , wire a^{18} , terminal 5 , switch lever H' , terminal 1 , branch wire section H^{21} , terminal b , switch lever B' , terminal b^2 , wire b^{18} , receiver b^{15} , and through the wire b^{16} to the ground. The induced current may be generated in like manner in the station B by the passage of a current from the positive pole of the battery B^6 through the wire b^{14} , terminal b^{13} , switch lever b^{12} , terminal b^{11} , wire b^{10} , transmitter b^7 , wire b^8 , primary coil b^9 and wire B^4 to the negative pole of the battery B^6 , and said induced current will pass from the secondary coil b^{17} which is connected to the ground H^{12} by one extremity of the wire b^{16} and by the wire B^4 through the opposite extremity of the wire b^{16} , the receiver b^{15} , wire b^{18} , terminal b^2 , switch lever B' , terminal 1 , switch lever H' , terminal 5 , wire a^{18} , receiver a^{15} , and wires a^{16} and H^{11} to the ground. It will be noted that when the switches H^2 and B^2 are shifted as just described, for transmitting speech from the line, so that the free ends of the levers

—H'—B'— rest upon the terminals —5—
b²—, the bell —H'— and the magnet —b⁵—
are cut out from the wire —H⁴— and the
section —H²²— of the branch wire —H—.
5 The main station is called in like manner
from the stations —C—D—E—F—G— of the
series connected to the wire —H—, it being
understood that the sections of the wire —H—
10 between the main station and the branch
station in circuit with the main station, are
utilized for the transmission of the current
and that the sections of the wire —H— on
15 the opposite side of said branch station re-
main cut out. The first branch stations —O—
and —R— of the series connected to the sec-
tions —T²¹—, —U²¹— of the wires —T—, —U—
20 are of similar construction to the station —B—,
previously described, connected to the section
—H²¹— of the wire —H—, and consist of switch
levers —O'—R'—, switches —O²—R²—,
switches or keys —O³—R³—, wires —O⁴—R⁴—,
25 —O⁵—R⁵—, batteries —O⁶—R⁶—, terminals
—o—r—, —o'—r'—, —o²—r²—, —o³—r³—,
—o⁴—r⁴—, magnets —o⁵—r⁵—, transmitters
25 —o⁷—r⁷—, wires —o⁸—r⁸—, primary coils
—o⁹—r⁹—, wires —o¹⁰—r¹⁰—, terminals —o¹¹—
r¹¹—, switch levers —o¹²—r¹²—, terminals —o¹³—
r¹³—, wires —o¹⁴—r¹⁴—, receivers —o¹⁵—r¹⁵—,
30 wires —o¹⁶—r¹⁶—, secondary coils —o¹⁷—r¹⁷—,
wires —o¹⁸—r¹⁸—, insulating bars —o¹⁹—r¹⁹—,
switches or keys —o²⁰—r²⁰—, terminals —o²¹—
r²¹—, —o²²—r²²—, circuits —X—Y—, and
35 switches —x—y— of similar construction and
arrangement to the corresponding parts —B'—
B²—B³—B⁴—B⁵—B⁶—b—b'—b²—b³—b⁴—b⁵—
b⁷—b⁸—b⁹—b¹⁰—b¹¹—b¹²—b¹³—b¹⁴—b¹⁵—b¹⁶—
b¹⁷—b¹⁸—b¹⁹—b²⁰—b²¹—b²²—I—i— of the tele-
40 phone station —B—. The remaining stations
—P—P'—P²—P³—P⁴— and —S—S'—
S²—S³—S⁴— of the separate series of branch
45 stations connected to the respective wires
—T—U— are here indicated only by rectan-
gles as previously stated, but it will be evi-
dence that they are composed of parts similar
in construction and arrangement to those of
45 the first stations —O—R— connected to said
wires —T—U— and just described.

The described main station —A— and
50 branch stations —B—C—D—E—F—G—,
—O—P—P'—P²—P³—P⁴—, —R—S—S'—S²—
S³—S⁴— may be of any desirable form, size,
and construction, and I have here described
55 only a simple form thereof, it being under-
stood that any construction and arrangement
of electric generators, wires, connections,
receivers and transmitters, suitable for use in
the transmission and reproduction of sound
may be used.

Connected in the circuits —I—J—K—L—
60 M—N—X— and —Y— are signals or bells
—B⁷—C⁷—D⁷—E⁷—F⁷—G⁷—O⁷—R⁷—, here
illustrated as composed of magnets —B⁸—C⁸—
D⁸—E⁸—F⁸—G⁸—O⁸—R⁸—, clappers or ham-
mers —B⁹—C⁹—D⁹—E⁹—F⁹—G⁹—O⁹—R⁹—
65 and vibrating shells —B¹⁰—C¹⁰—D¹⁰—F¹⁰—
F¹⁰—G¹⁰—O¹⁰—R¹⁰— of similar construction
to the like parts —H⁸—T⁸—U⁸—, —H⁹—T⁹—

U⁹— and —H¹⁰—T¹⁰—U¹⁰— of the bells —H'—
T⁷— and —U⁷— previously described, but it
will be evident that these signals or bells may 70
be of any desired construction capable of be-
ing set in motion through the medium of an
electric current. As these bells —B⁷—, —C⁷—,
—D⁷—, —E⁷—, —F⁷—, —G⁷—, —O⁷—, —R⁷—
may be of any desirable form, size and con-
struction to attract the attention of the opera-
75 tor at the stations provided therewith, it is un-
necessary to further illustrate and describe
said parts, especially as at Fig. 3 I have, in illus-
trating the switch —i—, presently described, 80
clearly shown the parts —B⁸—, —B⁹—, —B¹⁰—
of the bell —B⁷— in enlarged scale as opera-
tively mounted on the casing —I'— inclosing
the switch —i—. The switches —i—j—k—l—
—m—n—x—y— are of similar construction 85
and arrangement and I have here illustrated,
at Figs. 3, 4, 5, 6, 7, 8, 9, 10, 11, 12, 13, and 14,
the switch —i— of the first telephone station
—B— connected to the wire —H—. This
switch consists of a movable disk —i'—, which 90
forms a support for the terminal —i²— and is
provided with ratchet teeth —i³— upon its per-
iphery, a resetter or spring —i⁴— for return-
ing the disk or terminal support to its normal
position, an actuator or lever —i⁵— carrying 95
a terminal —i⁶— adapted to be brought into
registration with the terminal —i²— for clos-
ing the circuit —I— and carrying a dog —i⁷—
for engaging the teeth —i³— of the disk —i'—
and partially rotating said disk on its pivot 100
—i⁸— and a stop or dog —i⁹— for holding the
disk or terminal support —i'— in its adjusted
position. The switch —i— is preferably
mounted in a frame or box —I'—, Fig. 3,
105 which may be arranged in suitable proximity
to the ordinary telephone frame or box, not
necessary to herein illustrate, adapted to sup-
port the parts of the telephone station —B—,
and may, if desired, be a part of said box. The
pivot —i⁸— for the disk —i'— is, as best seen 110
at Fig. 3, journaled in the walls of the case
—I'— and one end of the spring —i⁴— is rigidly
secured to said pivot and the other to the disk
—i'— for automatically forcing said disk to its
115 normal position with the stop —i¹⁰— thereon
in contact with the stop —i¹¹— provided upon
the frame —I'—. The lever —i⁵— is hinged
upon the pivot —i⁸— and extends outwardly
120 beyond the periphery of the disk —i'— and the
terminal —i⁶— on said lever is arranged mid-
way between its extremities at a point directly
above the outer portion of the disk —i'—.
This terminal —i⁶— consists, preferably, of a
125 screw inserted into the side of an insulating
block —i¹²— secured by screws —i¹³— to the
under face of the lever —i⁵— and formed with
the head —i¹⁴— projecting upwardly in a side
cut out —i¹⁵— in the lever. The outer end of
the lever —i⁵— is deflected downwardly and
130 formed with the upright shoulder —i¹⁶— and
the dog —i⁷— is movable through an up-
wardly extending ear —i¹⁷— on said outer end
of the lever —i⁵— and through the shoulder
—i¹⁶— into engagement with the ratchet teeth

—*i³*—. The magnet —*b⁵*— is in proximity to one end of the lever —*i⁵*— which is provided with an armature —*i¹⁸*— opposite to the pole thereof and when the magnet is energized by the current passed therethrough in calling the station —*B*—, the lever —*i⁵*— is drawn forwardly as shown by an arrow at Fig. 4, and the disk —*i'*— is thereby partially rotated. The dog —*i⁹*— for holding the disk from re-

turn movement consists of a bell crank lever having one arm provided with a tooth —*i¹⁹*— adapted to engage the teeth —*i³*— of the disk —*i'*— and the other with a projecting lug —*i²⁰*— and is supported upon the pivot —*i²¹*— projecting from the wall of the outer case —*I'*—. A lever —*i²²*— is pivoted on a post —*i²³*— projecting from the case —*I'*— and is provided at one end with a slot —*i²⁴*— registered with the lug —*i²⁰*— and at the other with an armature —*i²⁵*— adapted to be drawn toward the magnet —*b⁵*— when the same is energized, thus disengaging the tooth —*i¹⁹*— from the teeth —*i³*— to permit retraction of the disk —*i'*— to its normal position by the spring —*i⁴*—.

—*i²⁶*— represents a cam mounted on a post —*i²⁷*— and adapted to engage a shoulder —*i²⁸*— on the dog —*i⁷*— and force the same as the lever —*i⁵*— is drawn forward by the magnet —*b⁵*—, out of engagement with the teeth —*i³*— against the action of the spring —*i²⁹*— surrounding said dog for throwing the same into action. It will thus be understood that when the armatures —*i¹⁸*— and —*i²⁵*— are in engagement with the magnet —*b⁵*—, the dog —*i⁷*— and the tooth —*i¹⁹*— are out of engagement with the teeth —*i³*— in order to permit retraction of the disk —*i'*— by the spring —*i⁴*— and that when the main circuit is broken immediately after being closed to effect the energization of the magnet —*b⁵*—, the lever —*i⁵*— is forced to its normal position by a spring —*i³⁰*— bearing against the same, the dog —*i⁷*— is then engaged with the teeth —*i³*— by the spring —*i²⁹*— and rides over said teeth against the action of said spring —*i²⁹*— and the tooth —*i¹⁹*— of the dog —*i⁹*— is forced into instant engagement with the teeth —*i³*— by a spring —*i³¹*— bearing against the dog —*i⁹*—.

The movement of the lever —*i⁵*— and the length of the teeth —*i³*— are so proportioned with reference to each other that by each movement of the lever, the disk —*i'*— is rotated forwardly a tooth and a half, but when the main circuit is instantly broken and the tooth —*i¹⁹*— forced against the teeth —*i³*—, the spring —*i⁴*— retracts said disk a half a tooth, so that the actual advance of the disk is but a single tooth, although the same moves forwardly a tooth and a half, since the disk also moves backwardly a half a tooth with each forward movement. This peculiar construction of the parts insures positive and automatic return of the disk should the current passed through the wire —*H*— and the magnet —*b⁵*— be of considerable duration, since the dog —*i⁷*— and the tooth —*i¹⁹*— are

then held out of engagement with the teeth —*i³*— and the spring —*i⁴*— instantly returns said disk to its normal position. On the contrary, when said current is of short duration, the dog —*i⁹*— is instantly returned and engages the disk —*i'*— without permitting the retraction thereof for more than half a tooth. It is thus evident that when a series of consecutive currents of short duration are passed through the magnet —*b⁵*— by rapidly closing and breaking the circuit through the wire —*H*—, the disk —*i'*— rotates forwardly one tooth for each pulsation of current passed through the main wire and when the current of long duration is passed through the magnet —*b⁵*— the disk is immediately retracted to its normal position. The disk —*i'*— is formed with a concentric groove or slot —*i³²*— arranged directly beneath the terminal —*i⁶*— and the groove is provided with serrations or notches —*i³³*— in its longitudinal edges. —*i³⁴*— represents a head or box supported in the groove —*i³²*— and formed with shoulders —*i³⁵*— resting upon the top and bottom faces of said disk, which is preferably reinforced along the edges of the slot —*i³²*—. The head is held from rearward lengthwise movement in the slot —*i³²*— by a plate —*i³⁶*— engaged with the serrations —*i³³*— in the edges of the slot —*i³²*— and from forward movement by a spring —*i³⁷*— having one end engaged with the forward face of the head —*i³⁴*— and the other with a plate —*i³⁸*— corresponding to the plate —*i³⁶*—. It will thus be noted that the terminals —*i⁶*— and —*i²*— are separated one from the other, and that, as the lever —*i⁵*— rotates the disk —*i'*—, the terminals are approximated for opening the circuit —*I*— and bringing the bell —*B'*— into action to attract the attention of the user of the station —*B*—.

In order that the approximation of the terminals may be readily perceived, I have, at Figs. 6 to 12 inclusive illustrated the movements of said terminals from their extreme separated position to their position assumed when in contact.

At Fig. 6 the terminals are in their extreme separated position, and, as clearly seen in this view, the terminal —*i²*— is forced downwardly by a coil spring —*i³⁹*— bearing against a shoulder —*i⁴⁰*— on said terminal. As the lever —*i⁵*— moves forwardly from its position shown at Fig. 6, it carries with it the disk —*i'*— and the terminal —*i²*— until it assumes its position shown at Fig. 7 and upon reference to these figures it will be noted that the relative distance between the terminals —*i²*— and —*i⁶*— has not been changed. As soon, however, as upon the breaking of the main circuit, the lever —*i⁵*— is retracted by the spring —*i³⁰*— to its position shown by dotted lines at Fig. 7, and full lines at Fig. 8, the terminals —*i²*— and —*i⁶*— are somewhat approximated, since the disk is held by the dog —*i⁷*— from backward movement after having been retracted a half tooth by the spring —*i⁴*—.

The terminal i^2 projects beneath the head i^3 and directly in the path of the projecting end thereof is a cam i^{41} for raising said terminal upwardly against the action of the spring i^{39} .

At Fig. 6 the projecting end of the terminal is shown at its greatest separation from this cam i^{41} ; at Fig. 7 it has approached the cam i^{41} a distance corresponding to the forward rotation of the disk i' a single tooth, and at Fig. 8, which represents the parts as in the position when the lever i^5 has twice moved the disk forward, it has still further approached the cam i^{41} . The current being quickly broken when the lever i^5 is in its position shown by full lines at Fig. 8, it moves backwardly to its position shown by dotted lines at Fig. 8, thus approximating the terminals i^2 and i^6 sufficiently so that the upper end of the terminal i^2 is directly beneath the forward edge of the lever i^5 , but, owing to the presence of the insulating block i^{12} directly above said terminal i^2 , the passage of electricity between the terminal i^2 and lever i^5 is absolutely prevented.

At Fig. 9 I have shown the parts in the position assumed when the lever i^5 has rotated the disk i' a third tooth, and, although the relative approximation of the terminals i^2 i^6 has not varied from that just described, the lower end of the terminal i^2 is at the foot of the upward inclination of the cam i^{41} . The lever i^5 , when retracted by the spring i^{30} from its position shown by full lines at Fig. 9 assumes its position shown by dotted lines at said figure and moves from above the terminal i^2 . As the lever i^5 moves the disk i' a fourth tooth the terminal i^2 is forced upwardly by the cam i^{41} against the action of its spring i^{39} , and, if the electric current is of duration sufficiently long to permit the return movement of the disk i' , the terminal i^2 immediately contacts with the terminal i^6 and the circuit I is closed. Owing to the contact of said terminals, the head i^{34} is held from retraction and the spring i^{37} is compressed by the return movement of the disk i' . When the main circuit is broken the lever i^5 moves to its position shown by dotted lines at Fig. 10, the spring i^{37} forces the head i^{34} rearwardly, the spring i^{39} depresses the terminal i^2 , and the head i^{34} is forced into engagement with the stop plate i^{36} . It will thus be seen that, when three currents of short duration are passed through the wire H , and are followed by a fourth of longer duration the terminals i^2 and i^6 of the circuit I are brought into contact and said circuit is closed. Should the fourth current be of the same duration as the three preceding, the lever i^5 returns to its normal position, and moves above the post i^{12} movable through insulating bushings i^{43} in the head i^{34} . If the fifth current is then of

longer duration the disk is moved forwardly a tooth and a half from its previous position, the insulating post is elevated by the cam i^{41} , and, when the disk i' returns, the insulating post encounters the terminal i^6 , as shown by dotted lines at Fig. 12, thus preventing the contact of the terminals i^2 i^6 and the closing of the circuit I . It will thus be seen that the terminals i^2 and i^6 can only come into contact when three currents of short duration are passed through the branch circuit wire H and are followed by a fourth of longer duration, and that should but three consecutive currents of either equal or unequal duration be passed through the main circuit, the switch i will be automatically reset and that should, as described, four currents of short duration be followed by one of either long or short duration, an insulating post intervenes between said terminals. The terminals i^2 and i^6 may, however, be so relatively arranged as to vary the number of currents of short duration required in connection with one of long duration to bring said terminals into contact, since the terminal i^2 may be moved on either side of its position shown at Figs. 4 and 5 by removing the stop plate i^{36} , forcing the head i^{34} to the desired position, and returning the plate i^{36} into engagement with the serrations i^{33} to form a stop for said head.

The circuit I consists of a positive wire I^2 from a battery I^3 to the pivot i^8 of the disk i' , the negative wire I^4 from the negative pole of the battery I^3 to the magnet B^8 of the bell B^7 and the wire I^5 from the magnet B^8 to the terminal i^6 .

As previously stated, the terminal i^6 is insulated from the lever i^5 , and consequently, there is no flow of electricity through the switch i until the terminals i^2 and i^6 are in contact. As the lever i^5 is continuously in movement when the current is passing, I obviate wear on the wire I^5 to the greatest possible extent by winding the same around the pivotal pin i^8 and running the same lengthwise of the lever i^5 until the terminal i^6 is reached.

As described, a separate battery I^3 is used for the circuit I , but it is evident that the battery B^6 may be provided with an extra pair of positive and negative poles connected to the wires I^2 I^5 I^4 , or that any other suitable electric generator may be used, and that the circuit I is not limited to any particular form of wiring.

The circuits $J-K-L-M-N-X$ and Y are each shown as composed of parts $J^2-K^2-L^2-M^2-N^2-X^2-Y^2$, J^3-K^3 , $L^3-M^3-N^3-X^3-Y^3$, $J^4-K^4-L^4-M^4$, $N^4-X^4-Y^4$, and $J^5-K^5-L^5-M^5-N^5$, X^5-Y^5 and switches $j-k-l-m-n-x$, y corresponding to the like parts I^2-I^3 , I^4-I^5-i of the circuit I .

The switches $j-k-l-m-n-x-y$ are

- constructed in the same manner as the switch i and are composed of corresponding parts as movable disks $j^2-k^2-l^2-m^2-n^2-x^2-y^2$, terminals $j^5-k^5-l^5-m^5-n^5-x^5-y^5$, terminals $j^6-k^6-l^6-m^6-n^6-x^6-y^6$, slots $j^{32}-k^{32}-l^{32}-m^{32}-n^{32}-x^{32}-y^{32}$, heads $j^{34}-k^{34}-l^{34}-m^{34}-n^{34}-x^{34}-y^{34}$, springs $j^{37}-k^{37}-l^{37}-m^{37}-n^{37}-x^{37}-y^{37}$, and insulating posts $j^{42}-k^{42}-l^{42}-m^{42}-n^{42}-x^{42}-y^{42}$ corresponding in construction and operation to the like parts $i^1-i^2-i^5-i^6-i^{32}-i^{34}-i^{37}$ and i^{42} of the switch i .

The switches $h-t-u$ of the circuit H^{31} previously described, which bring into action the respective bells $H^7-T^7-U^7$ of the main station, are also constructed in the same manner as the switch i and are composed of corresponding parts as movable disks $h'-l'-u'$, terminals $h^2-i^2-u^2$, levers $h^5-l^5-u^5$, terminals $h^6-l^6-u^6$, slots $h^{32}-l^{32}-u^{32}$, heads $h^{34}-l^{34}-u^{34}$, springs $h^{37}-l^{37}-u^{37}$ and insulating posts $h^{42}-l^{42}-u^{42}$ corresponding in construction and operation to the like parts $i^1-i^2-i^5-i^6-i^{32}-i^{34}-i^{37}$ and i^{42} of the switch i . It is therefore unnecessary to illustrate, in enlarged views, any of these switches $h-t-u-j-k-l-m-n-x-y$, it being understood that their respective terminals h^2-h^6 , t^2-t^6 , u^2-u^6 , j^2-j^6 , k^2-k^6 , l^2-l^6 , m^2-m^6 , n^2-n^6 , x^2-x^6 , y^2-y^6 and the terminals i^2-i^6 of the switch i are of unequal separation. To illustrate: the terminals h^2-h^6 are separated but slightly so that they are approximated by the forward movement of the disk i^1 a tooth and a half and the return movement of the disk a tooth and a half occasioned by the passage of a single current of long duration through the circuit H^{31} . The terminals t^2-t^6 are separated twice as far as the terminals h^2-h^6 and are approximated by the passage through the circuit H^{31} of a current of short duration followed by one of long duration. The terminals u^2-u^6 are separated three times as far as the terminals h^2-h^6 and are approximated by two currents of short duration followed immediately by one of long duration and as just fully described, the terminals i^2-i^6 are approximated by the passage of three currents of short duration followed by one of long duration.

Each pair of the terminals j^2-j^6 , $-k^2-k^6$, $-l^2-l^6$, $-m^2-m^6$ are separated a greater distance than the terminals of the switch next in advance thereof so as to be approximated by the passage of a current of long duration followed by a number of currents of short duration exceeding the number of currents of short duration for approximating the next preceding station when followed by a current of long duration.

As illustrated, the terminals x^2-x^6 , $-y^2-y^6$ are separated the same distance as the terminals i^2-i^6 but they may be separated a greater distance than the terminals

of the last stations $G-P^4$ of the series of branch stations connected to the branch wires $H-T$. This unequal separation of the terminals of the respective switches $h-t-u-i-j-k-l-m-n-x-y$ is readily effected as the respective heads $h^{34}-t^{34}-u^{34}-i^{34}-j^{34}-k^{34}-l^{34}-m^{34}-n^{34}-x^{34}-y^{34}$ are adjustable in the slots $h^{32}-l^{32}-u^{32}-i^{32}-j^{32}-k^{32}-l^{32}-m^{32}-n^{32}-x^{32}-y^{32}$ in the same manner as the head i^{34} is adjustable in the slot i^{32} . It will also be readily understood that the terminals of any of the switches $h-t-u-i-j-k-l-m-n-x-y$ are readily separated by the corresponding insulating posts $h^{42}-t^{42}-u^{42}-i^{42}-j^{42}-k^{42}-l^{42}-m^{42}-n^{42}-x^{42}-y^{42}$ when the currents of short duration passed through the circuit wires $H-T-U$ are in excess of the number designed to approximate said terminals when followed by a current of long duration; in the same manner that the terminals i^2-i^6 are separated by the post i^{42} when four currents of short duration are followed by one of long duration. It will also be evident that the disks $h'-t'-u'-i'-j'-k'-l'-m'-n'-x'-y'$ are automatically returned to position when a current of long duration is passed through the magnets $H^{29}-T^{29}-U^{29}$ $b^5-c^5-d^5-e^5-f^5-g^5-o^5-r^5$.

As previously stated, I have not herein illustrated the stations $P-P'-P^2-P^3-P^4$, $S-S'-S^2-S^3-S^4$, but have only indicated said stations by rectangles. It will be evident, however, that these stations are also provided with switches corresponding to, and operating in the same manner as, those previously described, and so arranged that the terminals of the switches of the branch stations of each series are of unequal separation in the same manner as the terminals i^2-i^6 , j^2-j^6 , k^2-k^6 , l^2-l^6 , m^2-m^6 , and n^2-n^6 of the stations $B-C-D-E-F-G$ of the series just described and connected to the circuit wire H are separated. These switches $h-t-u-i-j-k-l-m-n-x-y$ and the switches of the stations $P-P'-P^2-P^3-P^4$, $S-S'-S^2-S^3-S^4$ not illustrated nor described are a simple form of mechanism for carrying out my invention and may be of any desired form, size and construction to attain the desired end, that is, the bringing into action of a particular or predetermined signal of a series of connected stations without bringing the signals of any of the other stations into action.

As hereinbefore stated, the operator at one of the stations, as F , who wishes to call the central station, depresses the key F^4 into contact with the terminal f^4 and the electric current passes through the wire H and the intervening stations $E-D-C-B$ to the central station A and rings the bell H^7 thus attracting the attention of the operator at the main station. As each of these stations $E-D-C-B$ and A are provided with normally open switches $-k-j-i-h$ having their terminals of

unequal separation, the operator, at the branch station —F—, can ring any of said stations by regulating the number and duration of the consecutive currents passed through 5 the wire —H— by the contact of the key —F³—, and with the terminal —f⁴— and the withdrawal of said key from the terminal —f⁴— in the same manner that, as previously described, the operator at the main station 10 rings the signal bell of either of the branch stations connected thereto. Consequently, great inconvenience and annoyance in the use of telephones is obviated and a great saving in the cost and maintenance of telephone 15 systems effected since one of the branch stations connected to the same wire can call, without the aid, or even the knowledge of the main station, any other station connected on the same wire interposed between said branch 20 station and the main station.

The station —F— is provided with a switch or key —f²⁰— and with terminals —f²¹— and —f²²— mounted, respectively, on the wires —F⁵— and —H²⁶— as previously described, 25 and when the switch —f²⁰— is in contact with the terminal —f²²— an electric current is sent from the battery —F⁶— through the wire section —H²⁶— and if the number and duration 30 of the currents passed through the wire section —H²⁶— correspond to the number and duration of currents for bringing the terminals —n²—n⁶— into contact, the bell —G⁷— is brought into action thus attracting the attention of the operator at station —G—.

35 As previously described, each of the stations —B—C—D—E—F— is provided with keys —b²⁰—c²⁰—d²⁰—e²⁰—f²⁰—, terminals —b²¹—c²¹—d²¹—e²¹—f²¹— and —b²²—c²²—d²²—e²²—f²²—, whereby any of these stations may pass an 40 electric current through the outer or succeeding sections of the wire —H— and the succeeding branch stations connected thereto.

The stations —O— and —R— of the series of branch stations connected to the wires 45 —T—U— have been described as provided with keys —o²⁰—r²⁰— and terminals —o²¹—r²¹—o²²—r²²— and it will be readily understood that the stations —P—P'—P²—P³—, —S—S'—S²—S³— are provided with corresponding 50 switches and terminals. It will thus be readily understood that by my invention any branch station connected to a single wire may call, without the aid of the central station, a branch station on either side thereof, that the 55 central office is called by a branch station only when desired to connect with a branch station on a separate wire, as if the station —B— wishes to connect with the station —O— and that as the switch at one station is automatically closed, those at the others are automatically returned to their normal position.

It will be evident that the number of stations connected to a single wire may be varied at will; that the connections or wiring between the separate stations may also be varied and that, as previously described, the switches for controlling the action of the respective sig-

nals of the stations may also be greatly varied without departing from the spirit of my invention, which I do not limit to the precise 70 features of detail construction and arrangement.

The operation of my invention will be readily perceived from the foregoing description and upon reference to the accompanying 75 drawings, and it will be particularly noted that the essential feature thereof is a method of transmitting signals, and an apparatus for connecting telephone or other stations so that the stations are divided into series so arranged and connected that any one of the series may call another of the same series or may call a central office for connection with a station of another series. Moreover, as each of the stations is provided with an electric 80 generator, several pairs of stations may be simultaneously connected on the same wire and several messages may be simultaneously transmitted, as for instance, when six stations are connected to the same wire, the first and second, third and fourth, and fifth and sixth stations may be automatically connected as described.

Having thus fully described my invention, what I claim as new, and desire to secure by 95 Letters Patent, is—

1. The herein described electrical apparatus, the same consisting of a main station, branch circuit wires connected to the main station, branch stations connected to the branch 100 circuit wires, automatically operating switches, as —h—t—u—, at the main station connected to the branch circuit wires, and like operating switches as —i—j—k—l—m—n—o— and —r— in the branch circuit wires at the 105 branch stations; whereby the branch stations of separate circuits are connected through the medium of the main station or the branch stations of one of the circuits are connected without the medium of the main station, and 110 magnets at each branch station connected to said circuit wires for automatically closing one of said switches and simultaneously returning the others to their normal position, substantially as set forth. 115

2. The herein described electrical apparatus, the same comprising a main station, circuit wires connected to the main station, branch stations connected to the circuit wires, each being provided with a signal operating 120 electric circuit, normally open switches at the branch stations, each being provided with a movable mechanism for closing and breaking the signal operating circuit and a stop for holding a portion of said movable mechanism 125 in its adjusted position, and magnets at the branch stations connected to the movable mechanism and to the stops at said stations, and provided with armatures for operating said mechanisms to close the signal operating 130 circuits and for actuating the stops out of their operative position, substantially as and for the purpose specified.

3. The herein described electrical appara-

- tus, the same consisting of a main telephone station, branch circuit wires connected to the main station, branch stations connected to the branch circuit wires, automatically operating switches as —h—t—u—i—j—k—l—m—n—o— and —r— between the main station and the branch circuit wires and between the branch stations and their respective wires said switches being provided with movable mechanisms and with stops therefor whereby the branch stations of separate circuits are connected through the medium of the main station, or the branch stations of one of the circuits are connected without the medium of the main station, and movable resetters connected to said movable mechanisms for retracting the same when the stops therefor are out of operative position, substantially as specified.
- 20 4. The herein described electrical apparatus, the same comprising a main station, a circuit wire connected to the main station, branch stations connected to the circuit wire, independent signal operating electric circuits for the main and branch stations, normally open switches at said stations, each being provided with a movable mechanism for closing and breaking the signal operating circuit and with a stop for holding a portion of
- 25 30 35 said movable mechanism in its adjusted position, and magnets at said stations connected to said movable mechanisms and to said stops and provided with armatures for operating said mechanisms to close the signal operating circuits and for actuating the stops out of their operative position, substantially as and for the purpose set forth.
5. The herein described electrical apparatus, the same comprising a main station, a circuit wire connected to the main station, branch stations connected to the circuit wire, independent signal operating electric circuits for the main and branch stations, normally open switches at said stations, each being provided with a movable mechanism for closing and breaking the signal operating circuit and a stop for holding a portion of said movable mechanism in its adjusted position, magnets at said stations connected to said movable mechanisms and to said stops and provided with armatures for operating said mechanisms to close the signal operating circuits and for actuating the stops out of operative position, and a series of movable resetters connected to said movable mechanisms for retracting the same when the stops are out of their operative position, substantially as and for the purpose set forth.
6. The herein described electrical apparatus, the same comprising a main station, circuit wires connected to the main station, branch stations connected to the circuit wires, a terminal at each of the branch stations, a second terminal at each of the branch stations arranged to move from its normal position into contact with the first terminal, suitable actuating mechanisms between the circuit

wires and the second terminals for moving the same into contact with the first terminals, a magnet at each station and a plurality of armatures operated by each magnet, said armatures being connected to operate said terminal actuating mechanisms and electrical current generators at the main and branch stations independently operating said actuating mechanisms, substantially as and for the purpose specified.

7. The herein described electrical apparatus, the same comprising a main station, circuit wires connected to the main station, branch stations connected to the circuit wires, a plurality of armatures at each of the branch stations connected, substantially as described, to the circuit wires, and normally separated circuit terminals at each of said branch stations, connected, substantially as described, to said plurality of armatures, substantially as and for the purpose specified.

8. The herein described electrical apparatus, the same comprising a main station, circuit wires connected to the main station, branch stations connected to the circuit wires, electric magnets at the branch stations, normally separated electric circuit terminals at each of said branch stations, and a plurality of armatures for each of said magnets connected, substantially as described, to said terminals, substantially as and for the purpose set forth.

9. The herein described electrical apparatus, the same comprising a main station, a circuit wire connected to the main station, branch stations connected to the circuit wire, normally separated terminals at each of said stations, and a plurality of armatures at each of said stations connected, substantially as described, to said circuit wire and to said terminals, substantially as and for the purpose set forth.

10. The herein described electrical apparatus, the same comprising a main station, circuit wires connected to the main station, branch stations connected to the circuit wires, a terminal at each of the branch stations, a second terminal at each of the branch stations, a magnet at each station, and a plurality of armatures operated by each magnet and connected to the corresponding terminals for automatically connecting and disconnecting the same and electrical current generators at the main and branch stations, substantially as and for the purpose described.

11. The herein described electrical apparatus, the same comprising a main station, circuit wires connected to the main station, branch stations connected to the circuit wires, normally separated terminals at each of the branch stations, an automatically returning movable support at each branch station for connecting the separated terminals at said station, stops for holding the movable supports in their adjusted position, magnets connected to the circuit wires and provided with armatures connected to said movable

supports for operating the same to connect the terminals and connected to said stops for holding the same out of their operative position when one of the switches is closed, substantially as and for the purpose set forth.

12. The herein described electrical apparatus, the same comprising a main station, circuit wires connected to the main station, branch stations connected to the circuit wires, normally separated terminals at each of the branch stations, a movable support at each station for connecting the terminals at said station, stops for holding the movable supports in their adjusted position, magnets connected to the circuit wires and provided with armatures connected to said movable supports for operating the same to connect the terminals and connected to said stops for holding the same out of their operative position when one of the switches is closed, and resetters for automatically returning the supports when one of the switches is closed, substantially as and for the purpose specified.

13. The herein described electrical apparatus, the same comprising a main station, circuit wires connected to the main station, switches between the main station and the circuit wires, each provided with normally separated terminals, and with a movable support for connecting said terminals, branch stations connected to the circuit wires, switches between the circuit wires and their respective stations each provided with normally separated terminals and with a movable support for connecting said terminals, stops for holding the movable supports of the switches in their adjusted positions, magnets connected to the circuit wires and provided with armatures connected to said movable supports for operating the same to connect the terminals and connected to said stops for holding the same out of their operative position when one of the switches is closed, and resetters for automatically returning the supports when one of the switches is closed, substantially as and for the purpose specified.

14. The herein described electrical apparatus, the same comprising a circuit wire, stations connected to the circuit wire, generators at each of the stations, and connections between each station and the portions of the circuit wire on opposite sides thereof for passing a current from the generators at said stations through opposite sides of the circuit wire, substantially as and for the purpose set forth.

15. The herein described electrical apparatus, the same comprising a circuit wire, stations connected to the circuit wire automatic switches between each of the stations and the circuit wire for connecting said stations to the circuit wire, generators at each of the stations, and connections between each station and the portions of the circuit wire on opposite sides thereof for passing a current from the generator through opposite sides

of the circuit wire, and automatically closing one of said switches, substantially as and for the purpose specified.

16. The herein described electrical apparatus, the same comprising a main station, branch circuit wires connected to the main station, branch stations connected to the branch circuit wires, automatically operating switches between the main station and the branch circuit wires and between the several circuit wires and their respective branch stations, electric generators at the branch stations, and connections between the branch stations and the portions of the circuit wires on opposite sides thereof for passing a current from the generators at said stations through opposite sides of said circuit wires, substantially as and for the purpose specified.

17. The herein described electrical apparatus, the same comprising a circuit wire, stations connected to said wire and provided with normally broken electric circuits and with signals adapted to be brought into operation by the closing of the normally broken circuits, normally open switches connected to the normally broken circuits for automatically closing the same, magnets at said stations connected to said switches for automatically closing the said switches one at a time and closing the normally open signal operating circuits connected thereto, electric generators at said stations, and connections between the branch stations and the portions of the circuit wire on opposite sides thereof for passing a current from the generators through the opposite sides of said wire, substantially as and for the purpose set forth.

18. The herein described electrical apparatus, the same consisting of a main station, branch circuit wires connected to the main station, switching mechanism at the main station for connecting said branch circuit wires, automatically operating switches as *h*—*t*—*u*— at the main station connected to the branch circuit wires, signal mechanisms at the main station connected to said switches, like operating switches as *i*—*j*—*k*—*l*—*m*—*n*—*o*— and *r*— in the branch circuit wires at the branch stations, signals at the branch stations, generators at each of the stations and connections between each branch station and the portions of the circuit wires on opposite sides thereof for passing a current from the generators at said stations through opposite sides of the circuit wire, substantially as and for the purpose specified.

In testimony whereof I have hereunto signed my name, in the presence of two attesting witnesses, at Syracuse, in the county of Onondaga, in the State of New York, this 22d day of April, 1892.

GEORGE W. HEY.

Witnesses:

CLARK H. NORTON,
L. M. BAXTER.
